UNITED STATES PATENT OFFICE.

ISAAC K. SHERO, OF OKEMAH, OKLAHOMA.

CONCRETE-MIXER.

1,012,729.

Specification of Letters Patent. Patented Dec. 26, 1911.

Application filed November 23, 1910. Serial No. 593,912.

To all whom it may concern:

Be it known that I, ISAAC K. SHERO, a citizen of the United States, residing at Okemah, in the county of Okfuskee and 5 State of Oklahoma, have invented certain new and useful Improvements in Concrete-Mixers, of which the following is a specification.

This invention comprehends certain new 10 and useful improvements in concrete mixing machinery of the continuously operating type, and the invention has for its primary object an improved construction of rotary mixing drum arranged to operate 15 upon a relatively small amount of material in a continuous manner to effectively mix the ingredients, the machine being so arranged that the materials can be continuously fed into one end of the drum and 20 continuously discharged from the other end, or intermittently fed and discharged, as required, the drum being equipped with an improved construction of end gate to control the discharge.

25 A further object of the invention is, to produce in a machine of this character, an improved construction and arrangement of end gate for the mixing drum, said end gate being associated with and connected to a 30 discharge chute preferably extending transversely of the machine at the discharge end of the mixing drum, the chute being so mounted that it may be easily manipulated by a single operator and so related to the 35 end gate that the movement of the chute to its operative position will move the end gate away from the discharge end of the mixing drum and permit the mixed materials to flow out.

40 The invention also has for its object a mixing drum freely suspended from endless chains supported by sprockets on an actuating shaft, the weight of the drum and the contents thereof tending to securely hold 45 the drum in engagement with the chains whereby to impart to the drum the necessary rotary movement, a mixing drum which is provided with a novel and efficient arrangement of mixing blades and discharge sleeve 50 at the discharge end of the drum, and a mixing drum which is supported in and by a tilting and adjustable frame, whereby the inclination of the drum may be easily changed as required.

55 The invention also has for its object an improved initial mixing device forming part of the feed mechanism for the feeding

drum and embodying an improved rotary elevator preferably operated in the same manner as the mixing drum and from the 60 same driving elements, the elevator being adapted to receive the ingredients from the several hoppers of the feeding device simultaneously to tumble the same in order that the ingredients may be at least partially 65 mixed before they are passed to the mixing drum. And the invention also has for its object to generally improve this class of devices and to render them more efficient in 70 operation and commercially desirable.

With these and other objects in view as will more fully appear as the description 75 proceeds, the invention consists in certain constructions, arrangements and combinations of the parts that I shall hereinafter 80 fully describe and claim.

For a full understanding of the invention, reference is to be had to the following description and accompanying drawings, in 85 which:

Figure 1 is a side elevation of a concrete mixing machine constructed in accordance with my invention; Fig. 2 is a top plan view of the machine; Fig. 3 is a vertical longitudinal section thereof; and Fig. 4 is a 90 transverse sectional view of the lower portion of the discharging apparatus.

Corresponding and like parts are referred to in the following description and indicated in all the views of the drawings by 95 the same reference characters.

The supporting framework of my improved machine includes longitudinally extending sills 1 preferably mounted on trucks 2 on which ground wheels 3 are journaled, 95 whereby the machine may be easily moved from place to place.

At the rear end of the machine is the feeding mechanism, which comprises a casing 4, formed with a longitudinally extending 100 partition 5 dividing the casing into a sand hopper 6 and stone hopper 7. At one corner of the stone hopper 7, the casing 4 is formed with a right angularly shaped partition 8 designed to produce a cement hopper provided at its top with a hinged or other door, the sand hopper being provided at its top and at the rear end thereof with a shield 11. The materials are designed to be passed from the hoppers by a feeding 105 device 12 mounted upon a transversely extending shaft 13 journaled as at 14. The feeding mechanism also includes a circular rotary elevator 20 formed with a flanged

periphery and with channeled sides in which buckets 21 are secured, the buckets being adapted to travel in a transverse direction underneath the feeding device 12 so as to receive the ingredients therefrom and carry them upwardly in the rotation of the elevator. The flanged periphery 22 of the elevator is engaged by an endless chain 23 which suspends the elevator for its rotary movement and which is in turn suspended from and works over a sprocket wheel 24 secured to the rear end of a shaft 25. This shaft is loosely journaled in a bearing block 26, said block being formed on opposite sides with trunnions 27 mounted in a bearing bracket 28 secured to and extending upwardly from the cross bar 19. A spout 29 is connected to the rear edge of the casing 4 and is adapted to extend into the receiving end of a preferably tapering mixing drum 30, the larger end of the drum being the receiving end thereof. The spout 29 is mounted above the casing 4 and within the rotary elevator 20, and hence as the latter rotates, the ingredients will be at least partially mixed in the buckets 21 and will be dropped onto the spout 29 and conveyed by the latter into the mixing drum 30.

The mixing drum 30 is formed in the present instance with two channeled circumferentially extending tracks 31 around which endless chains 31^a extend to directly support the drum and to rotate the same about its longitudinal axis as the chains travel. These chains are in turn supported by and work on sprocket wheels 32 which are secured to a longitudinally extending shaft 33. This shaft is journaled near one end in a cross bar 34 which extends transversely and which has at its ends trunnions 35 mounted for a turning movement in vertical standards 36 secured at their lower ends to the sills 1. Connected to the cross bar 34 are two longitudinally extending parallel side bars 37 which project forwardly from the cross bar 34 and which are connected near their forward ends by a cross bar 38, the cross bar 34, longitudinal bars 37 and cross bar 38 forming a tilttable suspension frame for the drum. The longitudinal bars 37 of this frame have forwardly projecting ends 39 which embrace the adjacent posts 40 of a derrick which is mounted on the framework near the front end of the latter and which will be hereinafter more specifically described, said adjacent posts 40 being formed with apertures 41 designed to receive a supporting rod 42 upon which the forwardly projecting ends 39 of the bars 37 are adapted to rest. It will thus be seen that by varying the vertical position of the supporting rod 42, the drum supporting frame may be tilted and held at different inclinations so as to give more or less inclination to the mixing drum 30.

The drum shaft 33 is connected at its rear end to the shaft 25 before mentioned, by means of a universal joint 43 so arranged that the shaft 33 may be tilted, as required, without materially changing the pitch or position of the shaft 25. A bevel gear wheel 44 is secured to the drum shaft 33, said gear wheel meshing with a bevel pinion 45 secured to the inner end of a relatively short transverse shaft 46. The shaft 46 is journaled in a bearing 47 secured upon a ledge 48 formed on one of the longitudinal bars 37. A pulley or band wheel 49 is secured to the outer end of the transverse shaft 46 and a driving belt 50 extends over the said pulley and also around a pulley 51 mounted on the driving shaft 51^a of a motor 52 of any desired type, either electric, gasoline, or steam. A sprocket wheel 53 is also secured to the transverse shaft 46 and is connected by a chain 54 to a sprocket wheel 55 on the feeding shaft 18. The mixing drum 30 contains any desired number of mixing blades 56, the same being arranged in three spirally extending rows in the present instance and being of angular formation riveted or otherwise secured to the drum, the present arrangement producing a substantially continuous spiral feeding and mixing means from the receiving to the discharge end of the drum. At the discharge end of the drum the same is provided on its interior with a concave and rearwardly tapering trough 57 adapted to catch the materials as they are fed to this end of the drum in the rotary movement thereof and discharge the same. An end gate 58 is mounted at the discharge end of the mixing drum 30, said end gate in the present instance being in the form of a plate or disk, as shown, and being supported by springs 59 that are secured to a laterally disposed discharging and transferring chute 60. This chute is formed with depending arms 61 by which it is tiltably mounted intermediate of its ends on a rod 62 secured to and supported by transverse sills 63. The chute is provided at one end with a handle 64 by which it may be manipulated, and it will be understood that when the chute is in its normal inoperative and more nearly horizontal position, the end gate will be positioned across the discharge end of the mixing drum so as to retain the materials therein as long as required. Upon tilting the chute 60 by raising up upon the handle 64, the chute will be moved to a more inclined and operative position and at the same time, as the end gate is carried by the chute, the end gate will be moved away from the discharge end of the mixing drum to permit the materials to flow out of the latter. It is obvious that the chute may discharge the materials into any desired receptacle, as for instance into an elevating and dumping bucket, such as that

illustrated at 65 in Fig. 4, arranged for a sliding movement on the tracks 67 of conveyor standards 68.

By forming the gate 58 considerably larger than the discharge end of the mixing drum 30 and connecting it to the chute 60 by the springs 59, the gate will be retained in closed position no matter to what extent the discharge end of the drum may be adjusted by means of the pins 42 and apertures 4.

A sprinkling pipe 103 extends along one side of the mixing drum 30, being supported preferably by the standards 18 and rear-most derrick posts 40, the spray pipe turning into the receiving end of the drum to sprinkle the contents thereof. The pipe is provided with a controlling valve 104 of any desired type, and a hose 105 is connected to the valved end of the sprinkling pipe 103, being intended to convey the water to the pipe from any suitable source of supply; (not shown).

From the foregoing description in connection with the accompanying drawing, the operation of my improved concrete mixing machine will be apparent. In the practical use of the apparatus, the materials to be mixed are fed into the hoppers and are passed therethrough into the rotary elevator 20, from whence they are dropped onto the spout 29 and fed by the latter into the receiving end of the mixing drum 30. The weight of the drum and its contents insures the rotation of the drum as the shaft 33 rotates, and the ingredients will be thoroughly commingled by the action of the blades 56, being sprayed with water from the pipe 103. The concrete may then be discharged either continuously from the drum onto the laterally disposed discharging or transferring chute 60 and be transferred thereby into wheelbarrows or other receptacles, or if desired the discharge of the concrete from the drum may be intermittent and controlled by the operator at the handle 64.

Having thus described the invention, what is claimed as new is:

50 1. In a concrete mixing machine, a supporting frame including vertical standards, a bearing carried by said standards and swinging vertically thereon, a shaft mounted intermediate its ends in said bearing, 55 chain wheels carried by said shaft at opposite sides of said bearing, a mixing drum, chains engaging the chain wheels and extending around the mixing drum, and means for vertically adjusting said shaft to cause 60 it to swing with said bearings.

2. In a concrete mixing machine, a supporting frame, a mixing drum, means for rotating said drum, a gate operating to close

the discharge end of said drum, a chute mounted to swing beneath the discharge end 65 of said drum, and yieldable connecting means between said chute and gate.

3. In a concrete mixing machine, a supporting frame including vertical standards, a bearing member carried by said standards 70 and swinging vertically thereon, a transverse member having a bearing, longitudinal bars connecting said bearing member and transverse member, a shaft mounted intermediate its ends in said bearings, chain 75 wheels carried by said shaft at opposite sides of said bearing member, a mixing drum, and means for vertically adjusting said transverse member and the shaft supported thereby to change the inclination of 80 said drum.

4. In a concrete mixing machine, a framework, standards extending upwardly from the framework, a cross bar mounted to turn in said standards, side bars connected at one 85 end to said cross bar, posts extending upwardly from the framework, another cross bar connected to said side bars near the other ends of the latter, a rod adapted to be passed through said posts at different elevations and arranged to support the last 90 named ends of the side bars, a shaft journaled in said cross bars, sprocket wheels carried by said shaft on opposite sides of the first-named cross bar, chains passing 95 around said sprocket wheels, and a mixing drum suspended by said chains.

5. In a concrete mixing machine, a framework, standards extending upwardly from the framework, a cross bar mounted to turn 100 in said standards, side bars connected at one end to said cross bar, posts extending upwardly from the framework, another cross bar connected to said side bars near the other ends of the latter, a rod adapted to be 105 passed through said posts at different elevations and arranged to support the last named ends of the side bars, a shaft journaled in said cross bars, sprocket wheels carried by said shaft on opposite sides of the 110 first-named cross bar, chains passing around said sprocket wheels, a mixing drum supported by said chains, a gear wheel secured to said shaft, a transverse shaft supported on one of the side bars, a pinion meshing 115 with said gear wheel and connected to said transverse shaft, a motor, and a driving connection between said motor and the transverse shaft.

In testimony whereof, I affix my signature 120 in presence of two witnesses.

ISAAC K. SHERO. [L. S.]
